DESIGN FOR A DRESS

Maxwell Richter, New York, N. Y.

Application July 6, 1936, Serial No. 63,650

Term of patent 3½ years

To all whom it may concern:

Be it known that I, Maxwell Richter, a citizen of the United States of America, residing in Manhattan, county of New York, and State of New York, have invented a new, original, and ornamental Design for a Dress, of which the following is a specification, reference being had to the accompanying drawing, forming part thereof, wherein,

The characteristic feature of my design resides in the combination of horizontal tucks and shirring on the shoulders of the double collared dress, as shown.

I claim:

The ornamental design for a dress, substantially as shown and described.

MAXWELL RICHTER.
